US00D951956S

(12) **United States Design Patent** (10) **Patent No.:** **US D951,956 S**
(45) **Date of Patent:** **** May 17, 2022**

(54) **MEMORY CARD**

(71) Applicant: **HUAWEI TECHNOLOGIES CO., LTD.**, Shenzhen (CN)

(72) Inventor: **Jiangtao Yang**, Shenzhen (CN)

(73) Assignee: **HUAWEI TECHNOLOGIES CO., LTD.**, Shenzhen (CN)

(**) Term: **15 Years**

(21) Appl. No.: **29/658,385**

(22) Filed: **Jul. 31, 2018**

(30) **Foreign Application Priority Data**

Feb. 1, 2018 (CN) 201830049545.0

(51) **LOC (13) Cl.** **14-02**

(52) **U.S. Cl.**

USPC **D14/437**; D14/436

OTHER PUBLICATIONS

Yang, U.S. Appl. No. 29/658,383, filed Jul. 31, 2018, entitled "Card" total 5 pages.

(Continued)

Primary Examiner — Susan Moon Lee

(57) **CLAIM**

The ornamental design for a memory card, as shown and described.

DESCRIPTION

FIG. 1 is a front view of a first embodiment of a memory card showing my new design;

FIG. 2 is a front view of a second embodiment of a memory card showing my new design; and,

FIG. 3 is a front view of a third embodiment of a memory card showing my new design.

The rear, top, bottom, left side, and right side views are omitted and form no part of the claimed design.

All elements shown on the front surface of the card are flat and on the same plane as the front surface of the card.

1 Claim, 3 Drawing Sheets
